UNITED STATES PATENT OFFICE

FREDERICK W. SAUER, OF BROOKLYN, NEW YORK.

SAFETY-RELEASE FOR WRINGERS.

1,239,045.

Specification of Letters Patent.

Patented Sept. 4, 1917

Application filed December 28, 1916. Serial No. 139,264

To all whom it may concern:

Be it known that I, FREDERICK W. SAUER, a citizen of the United States, residing in the borough of Brooklyn, city of New York, county of Kings, and State of New York, have invented a new and useful Improvement in Safety-Release for Wringers, of which the following is a specification.

The object of the invention is to provide a safety release for wringers which is exceedingly simple in construction, instantly and easily releasable in event of emergency, and normally adapted to restrain the parts with perfect security. With these ends in view the invention comprises certain features of construction and combinations of parts, described hereinafter in their preferred embodiments.

In the accompanying drawings:
20 Figure 1 is a side elevation of the wringer in its normal condition;

Fig. 2 is a similar view with parts broken away and in section, showing the condition when the release is operated;

25 Fig. 3 is a fragmentary end elevation at one side of the machine;

Fig. 4 is a fragmentary elevation at the opposite side; and

30 Figs. 5 and 6 are enlarged detail perspective views.

The wringer frame 2, rolls 3, gearing 4, housing 5, boxes 6, pressure springs 7, pressure bar 8, and screws 9 are of usual or suitable construction.

35 The top rail 10, through which the screws 9 are threaded, has a fulcrum connection at one end with the frame and at the other end a releasing connection. At the one end a plate 11 is secured rigidly to the rail 40 and projects downward alongside the frame, terminating in an inturned portion 12 having an upturned end 13. A plate 14 is fixed to the side of the frame beneath the plate 11, and is formed with a slot 15 and with 45 an outwardly offset portion 16 immediately above this slot. The inturned portion 12 passes through the said slot, its extremity 13 engaging behind the same, so as to enable the rail to fulcrum or pivot at this end, without becoming separated, when the opposite end is released.

At the said opposite end is another plate 17, which is preferably a substantial duplicate of the plate 11, except that its inturned tip 18 does not have the upturned end 13. A trigger plate 19 is mounted upon the

adjacent side of the frame, between the same and the plate or tongue 17, the construction being such that it may be released from the tongue by a blow or pressure exerted inward toward the frame, thereby providing the easiest and quickest mode of operation in event of mishap. The said trigger plate may be transversely arched for sake of rigidity, and is preferably fulcrumed upon the frame by screws or bolts 20, passing substantially perpendicularly through the upper part of the trigger into the frame member. The under side of the head 21 of this screw is preferably convex 70 and the corresponding part of the trigger plate is curved as shown at 22 to enable it the more readily to rock upon the frame. A nut 23 upon the inner end inside the frame permits the trigger to be adjusted. 75

From this fulcrum the trigger declines downward and outward away from the frame to its point of engagement with the tip or shoulder 18, which it receives in an opening 24. The upward extension 25 of the trigger bears upon the side of the frame as a stop, limiting the outward movement of the trigger under the pressure of the springs. Thus the releasing device is self-holding in the normal condition, the effort 85 of the springs tending to rock the trigger oppositely to its releasing movement. The downward continuation of the trigger below the slot 24 is the part which is struck to relieve the pressure on the rolls. When this 90 is done the parts immediately separate as shown in Fig. 2.

What is claimed as new is:

1. In a wringer, the combination with a frame, rolls, and a top rail fulcrumed at one end upon the frame, of a tongue projecting from the other end of the top rail alongside the frame and terminating in an inturned tip, and a trigger mounted upon the side of the frame between the same and the tongue and having a recess engaged by said tip, the mounting of the trigger being such as to permit its disengagement from the tip by a blow or pressure exerted toward the frame. 105

2. In a wringer, the combination with a frame, rolls, and a top rail, of a tongue secured to and extending downward from said top rail, and a tongue-engaging trigger movably mounted upon the frame in such manner as to be released from the tongue by a blow delivered inward toward the frame. 110

3. In a wringer, the combination with a frame, rolls, and a top rail, of a tongue secured to and extending downward from said top rail and having a shoulder, a trigger plate having a formation intermediate its ends engaging said shoulder, and a fastening passing substantially perpendicularly through the upper part of the trigger into the frame and beneath the head of which the trigger may rock under inward applied pressure or blow upon its lower portion to release the tongue.
4. In a wringer, the combination with a frame, rolls, and a top rail, of a tongue secured to and extending downward from said top rail and having a shoulder, a trigger plate having a formation intermediate its ends engaging said shoulder, and a fastening passing substantially perpendicularly through the upper part of the trigger into the frame and beneath the head of which
- the trigger may rock under inward applied pressure or blow upon its lower portion to release the tongue, the said fastener having a head convex upon its under side, and the corresponding portion of the trigger plate being curved so as to rock upon the side of the frame. 25
5. In a wringer, the combination with a frame, rolls and a top rail, of a tongue extending downward from said rail, a trigger engaging said tongue, and means whereby the trigger is fulcrumed upon the frame above its point of engagement with the tongue, the trigger having a stop extension 30 above its fulcrum to bear against the frame. 35

In witness whereof, I have hereunto set my hand this 12th day of December, 1916.

FREDERICK W. SAUER.

In the presence of—

EMIL N. BAAR,

G. H. EMPEY.
